UNITED STATES PATENT OFFICE.

IRVING A. COOK, OF LANCASTER, OHIO.

SHOE-LAST.

1,019,602.

Specification of Letters Patent.

Patented Mar. 5, 1912.

Application filed April 1, 1910, Serial No. 552,808. Renewed October 7, 1911. Serial No. 653,452.

To all whom it may concern:

Be it known that I, IRVING A. COOK, a citizen of the United States, residing at Lancaster, in the county of Fairfield and State of Ohio, have invented certain new and useful Improvements in Shoe-Lasts, of which the following is a specification.

This invention relates to shoe lasts, and particularly to lasts of that type having 10 separate fore and heel sections which are connected together by a hinge member to allow the heel section to swing upon the fore section so that the last may be easily inserted in and removed from a shoe to which it may 15 be applied.

The particular objects of the present invention are to improve the hinge construction, and also to provide an improved latch device by which the sections are locked 20 when the last is straightened. The latch is so constructed that it will take up any wear in the parts, and hold the sections in rigid position even after extended use of the last.

Other novelties and advantages in the 25 design of the construction will be apparent from the following description and the accompanying drawings, in which—

Figure 1 is a sectional view of the last in straight position. Fig. 2 is a similar view 30 in flexed or broken position. Fig. 3 is a top view of the last. Fig. 4 is a perspective view of the latch member. Fig. 5 is a perspective view of the latch bushing.

Referring specifically to the drawings, 35 indicates the fore part of the last and 7 the heel part. These sections or parts meet or match on segmental lines, the meeting ends of the sections being cut to form upper and lower segmental faces 8 and 9 between 40 which is a shoulder at 10. These segmental faces are cut on the pivot pin 11 as a center, the radius of the face 9 being greater than that of the face 8, so as to form the shoulder 10 referred to, and the corresponding shoulder 45 of the heel section stops against the shoulder of the fore section when the last is straightened as in use.

The rear end of the fore part of the last is slotted or recessed as at 12, to receive the 50 hinge member. Said hinge member consists of a flat piece of metal having an arm 13 with an opening 14 at the front end through which the pivot pin 11 extends, said opening being enlarged horizontally, there- 55 by allowing the segmental meeting surfaces of the fore and heel sections to seat solidly

together, and eliminating any strain which might otherwise come on the hinge when in use. The rear part of the hinge member extends upwardly as at 15, at an angle to the 60 arm 13, and said rear part is fastened in a suitable kerf or slot in the heel section by means of rivets 16, at upper and lower ends respectively.

The rear upwardly extending arm 15 of 65 the hinge member is of proper width, and is so located, as to extend across or lap the joint between the meeting faces of the fore and heel parts, and in order to accommodate or receive the front edge of this arm, when 70 the last is broken, a groove 17 is cut in the upper part of the rear end of the fore section of the last, forming a continuation or extension of the slot 12 in which the hinge works. The hinge fits at a working fit in 75 the slots 12 and 17, and so the fore and heel sections are maintained in proper alignment, particularly by reason of the breadth of the hinge member, the arm 15lapping or extending across the joint throughout its whole 80 vertical length.

The upper end of the arm 15 is beveled or inclined as at 18, and this inclined edge is engaged by the latch which consists of a flat piece of metal 19 having a beveled face 85 or head 20 at its outer end, and provided also with an upwardly projecting finger piece 21 at said end, whereby it may be pushed in to unlock the parts when desired. This latch member works in a bushing 22, 90 consisting of a tubular piece of metal fastened in an appropriate recess in the rear end of the fore part of the last. The outer end of this bushing extends across the groove 17, but said end is notched as shown 95 at 23 to allow the finger piece 21 to be pushed in when the latch is released, and also to allow the passage of the edge of the hinge arm 15 when the last is broken. A spring 24 normally projects the latch member 100 to engage the hinge member and lock the parts when the last is straightened. At the end of the groove 17 is a stop piece 25, of metal, against which the end of the arm 15 stops, as shown in Fig. 2, when the last 105 is flexed.

The tapered end 20 of the latch member takes up any play in the parts which may be caused by the wear when in use, and at all times holds the heel down to the position 110 permitted or controlled by the shoulder 10, the pressure of the latch being toward or

in opposition to said shoulder. When the last is to be flexed, the latch is pushed in by pressure on the finger piece 21 until the edge of the hinge arm will ride over said latch, said edge passing up through the groove 17 until it reaches the stop 25. When the last is straightened the edge of the hinge arm passes off the head of the latch which is then forced out by the spring, and its wedge action against the beveled end of the hinge member holds the last parts in rigid position with respect to each other, irrespective of any wear.

What I claim as new is:—

- 15 1. A last comprising fore and heel sections, the fore section having a slot in its rear end and a groove extending upwardly from said slot, a hinge connecting said sections, said hinge having a forwardly extending arm pivoted in the slot and an upwardly projecting arm fixed to the heel section and sliding in said groove, and a sliding catch mounted on the fore section and working across said groove and engaging the upper end of said arm when the last is straightened.
- 20
- 25

2. A last comprising fore and heel sections, a hinge member connecting said sections, said member having an upwardly extending arm fixed to the heel section, and a forwardly extending arm pivoted at its front end to the fore section, the upper edge of said upwardly extending arm being inclined, and a spring latch member mounted on the fore section to the rear of the said pivot and having a beveled face engaging said edge when the last is straightened.

3. A last comprising a fore section having a slot in its rear end and a groove extending upwardly from said slot, a heel section, and a hinge member connecting said sections, said hinge member having a forwardly extending arm working in said slot and pivoted to the fore section, and an upwardly extending arm fixed to the heel section and working in said groove.

In testimony whereof, I affix my signature in presence of two witnesses:

IRVING A. COOK.
